[57] **CLAIM**

The ornamental design for a toilet roll holder, substantially as shown and described.

DESCRIPTION

FIG. 1 is a reduced front perspective view of a toilet roll holder embodying my new design.

FIG. 2 is a top plan view thereof.

FIG. 3 is a side elevational view taken from the left of FIG. 1.

FIG. 4 is a front elevational view taken thereof.

FIG. 5 is a side elevational view taken from the right of FIG. 1.

FIG. 6 is a bottom plan view thereof.

FIG. 1.FIG. 2.FIG. 3.FIG. 4.FIG. 5.FIG. 6.
